United States Patent Office

Des. 196,312
Patented Sept. 17, 1963

196,312

PLATE OR SIMILAR ARTICLE

Shigeru Masuda, Nagoya, Aichi, Japan, assignor to Noritake Co., Inc., New York, N.Y., a corporation of New York

Filed July 30, 1962, Ser. No. 71,102

Term of patent 7 years

(Cl. D44—15)

FIG. 1

FIG. 2

FIG. 1 is a plan view of a plate or similar article showing my new design, a repeat unit of the design being contained between dot-and-dash lines; and

FIG. 2 is a view of the design unit to enlarged scale. The plate is of a conventional configuration when viewed from the side and bottom thereof.

I claim:

The ornamental design for a plate or similar article, substantially as shown and described.
